UNITED STATES PATENT OFFICE.

GRATTAN W. THOMPSON, OF ST. LOUIS, MISSOURI, ASSIGNOR TO PETER H. MURPHY, OF EAST ST. LOUIS, ILLINOIS.

DRAFT-GEAR.

SPECIFICATION forming part of Letters Patent No. 759,572, dated May 10, 1904.

Application filed September 2, 1902. Serial No. 121,718. (No model.)

To all whom it may concern:

Be it known that I, GRATTAN W. THOMPSON, a citizen of the United States, and a resident of the city of St. Louis and State of Missouri, 5 have invented a new and useful Draft-Gear, of which the following is a specification.

My invention relates to draft-gears for cars and locomotives, and has for its principal objects to minimize the effects of sudden shocks 10 and strains, to provide for an efficient and increasing frictional resistance to the compression of the draft-gear and for the certain return thereof to normal position without undesirable shock, and to attain advantages 15 hereinafter mentioned.

My invention consists in the construction hereinafter described and claimed.

In the accompanying drawings, which form part of this specification, and wherein like 20 symbols refer to like parts wherever they occur, Figure 1 is a side view of my draft-gear as applied to a railway-car, and Fig. 2 is a plan view thereof. Fig. 3 is an end view of the inner cylinder. Fig. 4 is an end view of the 25 draft-gear assembled. Fig. 5 is a side view of the inner cylinder. Fig. 6 is a longitudinal sectional view of my draft-gear with one-half of the inner cylinder shown in elevation. Fig. 7 is a detail view of the end plate of the 30 inner cylinder; and Figs. 8, 9, 10, and 11 are detail views of the several friction-plates, respectively.

A hollow cylindrical shell 1 is provided internally with a plurality of helical grooves or 35 screw-threads 2 of high pitch. A second hollow cylindrical shell 3 is provided externally with helical ribs or screw-threads 4, adapted to coöperate with the helical grooves of the outer cylinder 1. The outer end of the inner 40 cylinder has an inwardly-extending flange 5. Inside of the inner cylinder and resting against the end flange 5 thereof is a circular plate 6, which has a hub 7 projecting through and beyond the outer open end of the inner 45 cylinder. This end plate 6 forms one abutment for one or more helical springs 8, extending through the inner cylinder. The outer abutment for said spring or springs 8 consists of a friction-piece or clutch 9, ar-

ranged near the inner end of the outer cylinder. This clutch or friction-piece 9 is a circular plate having on one side a central cylindrical hub or boss 10 and a polygonal extension 11 thereof and having on its outer side a plurality of elongated ribs 12 projecting 50 from its circumference parallel with its axis. These ribs 12 constitute, in effect, an interrupted or longitudinally-slotted cylindrical shell of the same diameter as that of the inner threaded cylinder 3. In order to 55 interlock with said ribs 12, the inner end of the inner cylinder 3 is slotted lengthwise, so as to form elongated projecting arms 13, which interlock with said ribs 12. By this arrangement the threaded cylinder 3 is allowed a considerable longitudinal movement without becoming disengaged from the clutch or friction-piece 9.

The clutch or friction-piece 9 bears flatwise against a friction-plate 14, which is made in 70 two sections and has a circular central opening 15 to permit it to fit over the circular hub 10 of the friction-piece 9. The periphery of this friction-plate 14 is provided with a series of teeth 16, which interlock with teeth 17, provided therefor on the inside of the outer cylinder 1. For the double purpose of strengthening the teeth 17 and furnishing an abutment for the friction-plate 14 the diameter of 75 the outer shell beyond the screw-thread is reduced and the teeth 17 cut in the shoulder thus formed.

Abutting flatwise against the friction-plate 14 is a circular friction-plate 18, which has a 80 hole 19 therein of proper size and shape to fit over and interlock with the polygonal extension 11 of the hub 10 of the clutch or friction-piece 9. Preferably this extension 11 and the hole 19 are rectangular; but other shapes adapted to interlock may be used. On its 85 other side this friction-plate 18 abuts flatwise against another friction-plate 20. This plate 20 is circular in form and has two sets of lugs or teeth 21 22 on its periphery, which engage in sockets or notches provided therefor in a 90 flange 23, arranged on the inside of the reduced end portion of the outer cylinder. One set of lugs or teeth 21 are the full thickness 95

of the plate 20, and the corresponding notches in the flange 23 extend through the full thickness of the flange. The other set of teeth 22 are flush with the inner face of the plate 20 and are only one-third the thickness thereof. The notches corresponding thereto are formed on the inner side of the perimeter of the flange 23 and extend only one-third the depth thereof. By this arrangement the bottoms of the shallow sockets form a stop or abutment to prevent the plate 20 falling out, but permit the friction-plate 20 to project a slight distance through and beyond the end of the outer cylinder 1, when the several friction-plates are jammed against each other.

The construction hereinbefore described is mounted on the cars or locomotive in the same general way as other draft-gears. As shown in Figs. 1 and 2, it rests between the upper and lower arms of a yoke 24, which is fastened to the draw-bar 25 of the car-coupler 26. A follower-plate 27 intervenes between the draw-bar 25 and one end of the draft-gear, and a follower-plate 28 intervenes between the other end of said draft-gear and the loop of the yoke 24. These follower-plates 27 and 28 are supported and mounted in any suitable manner, their respective movements being limited in one direction by ordinary draft-lugs 29.

The operation of my device is as follows: In the normal positions of the draft-gear the plate 20 and the hub 7 of the plate 6 project beyond the ends of the respective cylinders 1 and 3, being held by the springs 8 against the respective follower-plates 27 and 28. When a pull is exerted upon a car-coupler 26, its force is transmitted through the draw-bar 25 and yoke 24 and the follower-plate 28 against the projecting hub 7 of the plate 6 at the end of the inner cylinder. As the follower-plate 27 at the opposite end of the draft-gear is prevented from moving forwardly by reason of its contact with its draft-lugs 29 in its normal position, the pull transmitted through the yoke and follower-plate 28, acting upon the hub 7, forces its plate 6 inwardly against the force of the springs 8. When the hub has been forced in flush with the end of the inner cylinder, the continued pull forces the inner cylinder endwise into the outer cylinder. The interlocking threads permit this movement, but interpose a considerable resistance thereto in the form of friction. At the same time such threads cause a rotary movement of the cylinders upon each other or of one cylinder upon the other. As the friction-plates 14 and 20 are interlocked by teeth to the outer cylinder 1 and the friction-plates 9 and 18 are interlocked by the clutch and polygonal extension 11 of its hub 10 to the inner cylinder 3, each of the four friction-plates has a motion transmitted to it from its corresponding cylinder, and the motion of each plate is in the opposite direction to that of the friction-plate abutting against it.

The friction thus caused by each friction-plate, grinding or sliding on its neighbor increases more and more as the pull increases and the springs 8 are compressed thereby. When the pull is released, the end of the plate 20 and the hub 7 on the end plates 6 are forced out beyond the ends of the respective cylinders and the friction-plate 14 is forced back against the shoulder or abutment provided therefor on the inside of the outer cylinder. The pressure of the spring is thereby cut off from the remaining friction-plates 18 and 20, so that the friction-plate 18 rests loosely between the plates 14 and 20, and the friction caused by its rotation is very slight and negligible. In order to restore the draft-gear to its normal position, therefore, the spring merely has to overcome the friction between the clutch-plate 9 and the plate 14 and the friction between the screw-threads 2 and 4. In order to reduce the latter, those faces 30 of the threads which are working when the draft-gear is being returned to normal position are arranged at right angles to the axis thereof, whereas the other meeting faces 31 (which are the working faces when the spring is being compressed) are arranged at a comparatively small angle to the axis, so as to wedge more tightly together in operation. In order to reduce the area of the surfaces in contact during the retracting movement, it is desirable to true up or finish the square faces 30 for only a portion of the length of the thread, the remaining portion being undercut to render it inoperative. It is also desirable to make the threads fit loosely, so as to allow a slight endwise play of the cylinders. In operation the spring upon the release of the pull which compressed it will force the plate 6 against the end flange 5 of the inner cylinder with a sudden shock, which aids considerably in loosening the two cylinders and starting their return movement.

When the gear is required to resist a buffing force, its operation is similar to that above described with reference to the pulling force, except that the follower-plate 27 moves and the follower-plate 28 is stationary during the buffing action. Consequently the draft-gear constitutes a buffing apparatus and is capable of use as such independently of its function as a draft-gear, and I do not wish to restrict myself to the use thereof in connection with railway-cars and locomotives.

Obviously the construction hereinbefore described admits of considerable modification without departing from my invention. For instance, the friction-plate 14 may be formed with its outer face hollowed out conically, and the plate 18 may be formed with its inner face projecting conically, in which case the hub 10 practically disappears and the polygonal extension 11 is formed directly on the plate 9. So, also, the friction-plates may be eliminated and the friction of the helical guides

or ribs alone relied on for the resistance. In such case two inner cylinders interlocked by longitudinally-extending arms and threaded with the same or different pitches may be 5 made to work in corresponding threads in the inner cylinders, and the spring may abut against the closed ends of these inner cylinders.

What I claim is—

1. A railway draft-gear comprising two cylinders provided with internal and external helical guides of steep pitch arranged to co-operate and a spring tending to separate said cylinders endwise and arranged to turn bodily 15 with the inner cylinder.

2. A railway draft-gear comprising two cylinders provided with internal and external helical guides of steep pitch arranged to co-operate, and a spring tending to separate said 20 cylinders endwise, said guides being arranged throughout their entire length to permit a slight endwise play of the cylinders.

3. A railway draft-gear comprising two cylinders provided with internal and external 25 threads of steep pitch arranged to co-operate, and a spring tending to separate said cylinders endwise, the faces of said threads which are working on the return movement of the draft-gear being substantially perpendicular 30 to the axis and the other faces being considerably inclined thereto.

4. A railway draft-gear comprising two cylinders provided with co-operating internal and external helical guides of high pitch, the inner 35 cylinder having longitudinally-projecting arms at its inner end and a clutch-plate having arms to interlock therewith, and a plurality of friction-plates arranged to interlock with the outer cylinder and said clutch-plate 40 respectively and arranged to be jammed flatwise together, and a spring tending to separate said cylinders endwise, substantially as described.

5. A railway draft-gear comprising two cylinders provided respectively with internal and 45 external helical ribs of steep pitch arranged to interlock, a plurality of friction-plates arranged to be jammed together flatwise and the abutting plates being fastened to move with 50 different cylinders, substantially as described.

6. A railway draft-gear comprising two cylinders provided respectively with internal and 55 external helical ribs of steep pitch arranged to interlock, a plurality of friction-plates arranged to be jammed together flatwise and the abutting plates being fastened to move with different cylinders, and a spring bearing against the innermost friction-plate and a piece at the opposite end of the inner cylinder, substantially as described.

7. A railway draft-gear comprising two cylinders provided respectively with internal and 65 external helical ribs of steep pitch arranged to interlock, a plurality of friction-plates arranged to be jammed together flatwise and the

abutting plates being fastened to move with different cylinders and a longitudinally-movable end plate for the opposite end of the inner cylinder having a hub normally projecting beyond said end, and a spring bearing against 70 said end plate and the innermost friction-plate, substantially as described.

8. A railway draft-gear comprising two cylinders provided with interlocking guides of steep pitch, an inner shoulder near the end of 75 the outer cylinder, a longitudinally-movable friction-plate adapted to abut endwise against said shoulder but locked against rotary movement relative to said outer cylinder, a longitudinally-movable friction-plate arranged to 80 project beyond the end of the outer cylinder, and one or more friction-plates between said above-mentioned plates, alternate friction-plates being fastened to rotate with the respective cylinders, and a spring tending to 85 separate said cylinders endwise, substantially as described.

9. A railway draft-gear comprising two cylinders provided with interlocking helical guides of a steep pitch, a shoulder inside of 90 said outer cylinder near the end thereof, a longitudinally-movable friction-plate adapted to abut against said shoulder but interlocked with said outer cylinder to move therewith, a longitudinally-movable friction-plate arranged to 95 project beyond the end of the outer cylinder but interlocked to rotate therewith, a longitudinally-movable clutch-piece interlocked with the inner cylinder to rotate therewith, and a longitudinally-movable friction-plate 100 between said above-mentioned friction-plates and interlocked with said clutch to rotate with the inner cylinder, and a longitudinally-movable end plate for the outer end of the inner cylinder having a hub projecting beyond the 105 end thereof, and a spring bearing against said clutch-piece and said end plate, substantially as described.

10. A railway draft-gear comprising two cylinders provided with interlocking helical 110 guides of steep pitch, a shoulder inside of said outer cylinder near the end thereof, a longitudinally-movable friction-plate adapted to abut against said shoulder but interlocked with said outer cylinder to move therewith, 115 a longitudinally-movable friction-plate arranged to project beyond the end of the outer cylinder but interlocked to rotate therewith, a longitudinally-movable clutch-piece interlocked with the inner cylinder to rotate therewith, and a longitudinally-movable friction-plate 120 between said above-mentioned friction-plates and interlocked with said clutch to rotate with the inner cylinder, and a spring tending to separate said cylinder endwise, substantially 125 as described.

11. A railway draft-gear comprising two cylinders provided with interlocking helical guides of steep pitch, a shoulder inside of said outer cylinder near the end thereof, a longi- 130

tudinally-movable friction-plate adapted to abut against said shoulder but interlocked with said outer cylinder to move therewith, a longitudinally-movable friction-plate arranged to project beyond the end of the outer cylinder but interlocked to rotate therewith, and a clutch consisting of a friction-plate having on one side arms adapted to interlock with longitudinally-extending arms on the inner cylinder and having on the other side a central hub extending through the first-mentioned friction-plate with a polygonal extension thereon, a longitudinally-movable friction-plate having a central opening fitting over said polygonal extension, and a spring tending to separate said cylinders endwise, substantially as described.

12. A railway draft-gear comprising two cylinders provided with interlocking helical guides of steep pitch arranged to permit slight endwise play of the cylinders, a shoulder inside of said outer cylinder near the end thereof, a longitudinally-movable friction-plate adapted to abut against said shoulder but interlocked with said outer cylinder to move therewith, a longitudinally-movable friction-plate arranged to project beyond the end of the

outer cylinder but interlocked to rotate therewith, a longitudinally-movable clutch-piece interlocked with the inner cylinder to rotate therewith, and a longitudinally-movable friction-plate between said above-mentioned friction-plates and interlocked with said clutch to rotate with the inner cylinder, and a longitudinally-movable end plate for the outer end of the inner cylinder having a hub projecting beyond the end thereof, and a spring bearing against said clutch-piece and said end plate, substantially as described.

13. A railway-gear comprising two cylinders provided with coöperating internal and external helical guides of steep pitch, the inner cylinder having longitudinally-projecting arms at its inner end, and a plate having arms to interlock therewith, and a spring bearing endwise against said plate and the opposite end of the inner cylinder, and friction-plates arranged to coöperate with said cylinders.
